ANDERS JORDAHL, OF NEW YORK, N. Y.

FILTER MEDIUM FOR AIR FILTERS.

Application filed August 20, 1924. Serial No. 733,151.

This invention relates to a filter medium for air or gas filters of the dry or semi-dry type and it specifically relates to a medium which can be used either with or without a frame, which frame may constitute a filter unit. It is an object of this invention to provide a filter medium constructed of knitted flat wire to constitute a knitted metal fabric which can be easily handled and washed. It is a further object of the invention to provide a fabric of flat metal wire or other suitable material, so that the flat wire will be angularly arranged in order that a low resistance is offered to the passage of the air therethrough. A still further object of the invention is to arrange any suitable number of layers of the knitted wire fabric together so that the air will have a tortuous path therethrough, due to the angularly arranged wires which at the same time will offer a very low resistance to the air. By the use of a fabric material composed of flat metal strands in contradistinction to such filter materials as mineral wool, the possibility of any fibers working loose or being broken off and carried into the clean air duct of the filter is obviated. A further advantage resides in the fact that the metal fabric can be stretched or pressed in order that the wire may present any desired angle to the direction of the flow of the air. The present invention has for its principal object to provide a novel filter medium comprising a knitted fabric, made up from flat or ribbon-like preferably metallic wire, which is employed to form a filtering body by folding the knitted fabric material upon itself, or by crumpling or balling up the same, or by otherwise aggregating sheets or layers of the same to build the filtering body to any desired mass or size. The novel metallic fabric, when knitted from flat or ribbon-like metallic wire, produces a fabric member or sheet in which the flat or ribbon-like strands are twisted or turned by the formation of inter-knit loops, into constantly varying angles, so that, when a plurality of folds, sheets or layers of such fabric are brought together to form a mass of desired size, a highly porous filter body is produced which possesses an exceedingly great number of intercommunicating interstices forming a labyrinthic structure throughout the entire mass. The filter body thus formed may easily be made to possess greater or less density, as the special conditions of use to which the same is put may require, because of the compressibility and resiliency thereof, by virtue of which the sheets or layers of the fabric forming the filter body may be either more or less loosely or more or less tightly compacted together. Even when highly compressed, the twisted or knitted metallic strands will tend to produce that irregularity or staggered relation between the loops of contacting strands of adjacent superimposed sheets or layers calculated to always assure the formation of the said labyrinthic interstices which are adapted to render the filter body pervious to the percolation therethrough of the fluid desired to be filtered, while at the same time rendering the mass efficiently adequate to separate and capture the solid particles or impurities desired to be removed from the fluid filtered therethrough. Other objects will be apparent from the following specification, taken in connection with the accompanying drawing, in which like reference characters indicate like parts throughout, and in which:

Fig. 1 is an elevation of a filter unit showing a part broken away to show the filter medium.

Fig. 2 is a vertical section through the filter unit.

Fig. 3 is an elevation showing a section of the knitted flat wire fabric.

Fig. 4 is an elevation of a detail of the wire fabric of Fig. 3 on a greatly enlarged scale, and

Fig. 5 is a section taken on line 5—5 of Fig. 4.

The filter medium comprises a sheet or layer 1 which is knitted from a flat or flexible ribbon-like wire into the sheet by any suitable method. These knitted strands are of metal of such thinness and flexibility that they will readily yield to the application of forces applied in the plane of the fabric sheet or at right angles to such plane for the purpose of varying the spaced relation of the adjacent strands, with respect to each other. Referring to Figs. 3 and 4 it will be noted that the wales of knit material are formed by the ordinary interknitting of the loops of each course with the course succeeding, thus producing a fabric having the ordinary interlooped loops. A strand of this fabric comprises the side portions 2 connected in-

tegrally at each end by the loop portions 3. From Fig. 5 it will be seen that the sides 2 are angularly arranged, that is they are preferably arranged angularly to the direction 5 of the air, the arrow in Fig. 5 representing the direction of the air through an air filter. The loop portion 3 may also be angularly arranged if desired and this is accomplished by regulating the amount of stretch which 10 the fabric is subjected to, either before or after it is inserted into the filter frame. The amount of angularity presented by the sides 2 and the loop 3 can be varied by stretching or pressing it either before or 15 after it is placed in the frame of the filter unit.

The sheets of wire fabric 1 are arranged in a filter unit frame 4 either in layers or in any other suitable manner. Preferably the 20 front and rear sides of this frame are provided with a screen 5 which is adapted to hold the sheets of fabric in place. A pair of handles 6 on the frame 4 permits of easy handling of the unit.

25 The numeral 7 indicates the edge or thickness of the wire in Fig. 4 but such thickness can of course be varied as can the width of the wire, since such details depend upon the service required. Due to the fact that a 30 sheet of this medium can be stretched in any direction it can be easily packed in the frame 4 and can also be easily cleaned. The filter which is formed by the plurality of layers of knitted fabric is preferably of the semi- 35 dry type which means that the layers of fabric are coated with a viscose material either by immersion or by otherwise coating the layers. This is differentiated from a dry filter by the fact that that type is not coated or immersed in any fluid or viscose substance and a wet filter utilizes water or the 40 like fluid.

The sheets 1 of the air and gas filter frame 45 may comprise knitted sheets having different size meshes, that is each sheet may have a mesh either smaller or larger than the mesh of the sheet immediately adjoining. In this way the larger mesh sheets may be arranged in front or the dirty air side, and 50 the small mesh sheets may be arranged in the rear, or the clean air side. On the drawing the dirty air side is the side having the handles 6 and the other side is the clean air side. Thus a plurality of sheets may be 55 arranged wherein the size of the mesh of each sheet progressively diminishes. The flat or ribbon-like metallic wire has runs formed into interlocked or interknit loops, whereby the desired fabric members of 60 width and length to provide a suitable surface area are produced. In knitting the wire to form the fabric, the same, as it is turned to shape the loops, is subjected to more or less torsional twisting, which results in the production of the loop forma-

tions conventionally shown in the drawings. The said formations, in practice, do not assume the strict geometrical form and distribution shown in the drawings, but are rather more or less irregularly distributed 70 throughout the fabric surface at each side thereof, with the result that the said surfaces are irregularly or unevenly roughened by the projecting angularities provided by the turns or twists of the flat or ribbon-like 75 wire. When folds, sheets, or layers of the fabric are aggregated into a desired mass, the thus irregularly or unevenly roughened meeting surfaces of adjacent folds, sheets or layers, more or less interlock and combine 80 or cooperate one with another to form a structure having the intercommunicating interstices providing tortuous air passages substantially uniformly distributed throughout 85 the entire filter mass.

90 The density of the mass forming the filter body may be more or less varied, as conditions of use may require, by compressing the superimposed folds, sheets or layers thereof more or less tightly together. Even when a mass of relatively great density is 95 desired, it may be obtained without danger of losing the characteristic indicia of the structure above described, since the uneven or irregularly roughened surfaces of the fabric, due to the multiplicity of interlocked strand loops distributed thereover, will always tend to produce sufficient separation of the component folds, sheets or 100 layers as to assure the requisite low air pressure resistance of the structure.

105 It will be understood that I may use metallic wire of any kind in the production of the fabric element of the filter medium as conditions of use may require. There 110 may be materials other than metal by which the physical characteristics of the fabric above pointed out may be attained, and which may be found suitable for certain kinds of filtration work, hence I deem such 115 material equivalent to metal within the scope of my present invention. It will also be understood that I may knit the fabric from single, double or compounded strands as may in any special case be desirable.

115 I claim as my invention:

1. An air and gas filtration medium consisting of a plurality of layers of knitted fabric, each layer consisting of flexible ribbon-like strands forming angularly arranged baffles to the air relative to the plane of the layer.

120 2. An air and gas filtration medium consisting of a plurality of layers of knitted fabric, each layer consisting of ribbon-like twisted metal strands which are adapted to be irregularly arranged relative to the strands of the other layers so that the loops and side portions of each strand form baffles for the reception and retention of dust.

particles and the irregularly arranged strands provide an interrupted path for the air current.

3. An air and gas filtration medium consisting of a plurality of layers of knitted fabric, each layer consisting of flexible metal strands which are irregularly arranged relative to the strands of the other layers so that the interlooped loops and side portions of each strand form reception and retention means for the dust particles and the irregularly arranged strands provide a tortuous path for the air current.

4. A filter medium comprising a plurality of layers of fabric material knitted from ribbon-like strands, said fabric being formed into a filter body providing a labyrinthic structure throughout its mass.

5. A filter medium consisting of a compressible metallic structure comprising a plurality of layers of knitted fabric, each layer comprising a multiplicity of interlocked relatively movable metallic strands adapted, under compression of the material to assume a comparatively compact relationship to each other to thereby vary the effective resistance of the metallic structure to the passage of fluid therethrough.

6. A filter medium consisting of a compressible metallic structure comprising a plu-

rality of layers of knitted fabric, each layer comprising a multiplicity of flexible metallic strands connected with each other and each strand having spaced portions independently yieldable with respect to the adjacent strands whereby said spaced portions of the strands may be disposed in comparatively compact relationship to each other by compression of the metallic structure to thereby vary the effective resistance of said structure to the passage of fluids therethrough.

7. In an air and gas filter, a filter medium embodying a plurality of layers of filtering material, including a metallic structure having its parts in definitely-fixed relations to each other in intercepting relation to the path of flow of the air, and said structure consisting of flat flexible metallic strands, the contiguous strands having angularly disposed interlocked loops presenting a multiplicity of variously inclined air baffling surfaces with relatively large intervening voids, the area of said voids and the relative angular disposition of said interlocked loops in the metallic structure being initially fixed by relatively flexing said metal strands.

In testimony whereof I affix my signature.

ANDERS JORDAHL.
